UNITED STATES PATENT OFFICE.

ELMER E. HICKEN, OF COLLINGSWOOD, NEW JERSEY.

LOCOMOTIVE-TENDER TANK.

Application filed August 19, 1926. Serial No. 130,305.

The object of my invention is to simplify the construction of a tender tank, to obviate the difficulties encountered at the curvilinear joints between the fuel box and the water tank.

The improved fuel box extends from the front of the tank to the front end of the tender, forming a rectangularly shaped box. This construction eliminates the curvilinear joints between the fuel box and the water tank and straight joints are substituted therefore. The invention relates to other details of construction which will be described hereafter.

15 In the accompanying drawings:

Fig. 1 is a longitudinal sectional view on the line 1—1, of Fig. 2;

Fig. 2 is a plan view of my improved tender tank for locomotives;

20 Fig. 3 is a transverse sectional view on the line 3—3, Fig. 1;

Fig. 4 is a transverse sectional view on the line 4—4, Fig. 1;

Fig. 5 is a perspective view showing the 25 upper and lower plates of the water tank portion of the tender;

Fig. 6 is a detached perspective view of the shaped angle bar;

Fig. 7 is a detached view of one of the 30 dash plates; and

Fig. 8 is a view illustrating a detail of construction.

The tender tank has a cylindrical section 2, and a segmental section 3, the segmental 35 section extending under the fuel box 4.

The bottom plate 1 of the tender tank is preferably made in one piece, segmental in form as shown in Fig. 5, and extends the full length of the tender.

40 The upper portion of the cylindrical section 2 of the tank is made of two segmental plates 1^a—1^a, with a seam 16 at the top, the lower edges of said upper portion being connected to the edge of the bottom plates as shown in Fig. 5.

Two longitudinal dash plates 5—5 are arranged on edge and are flanged at the lower edge as at 6 and at the upper edges as at 7. The plates as shown in Figs. 1 and 7 are

50 preferably made in two pieces 5^a and 5^b, riveted or welded together. The pieces 5^b are beveled to support the inclined plate 11 forming the rear of the fuel box and an end of the water tank.

55 The inclined side plates 8 of the fuel box are attached to the flanges 7 of the dash

plates 6, as shown in Fig. 4, and to the vertical side plates 13 of the tender. This construction is very rigid and substantial. The portions 5^a of the dash plates form the 60 lower side walls of the fuel box 4, as shown in Fig. 4.

The bottom plate 9 of the fuel box extends from the front of the tender to the transverse plate 10 which acts as a cross-brace and as a lower support for the inclined plate 11 which is attached to the transverse plate 12 at the front end of the cylindrical section 2 and to the bottom plate 9. 70

An angle plate 13 connects the plate 10 to the inclined plate 11.

Extending from each dash plate 5 to the lower edges of the side plates, on a line with the bottom plate 9 are bottom plates 9^a—9^a. 75 These plates rest on the upper edge of the segmental bottom plate 1 and form the bottom of the front upper sections of the water tank.

An angle-bar 14, shown clearly in Fig. 80 6, has two horizontal portions 14^a, which connect the semi-cylindrical bottom plate 1 to the bottom plates 9^a, and has a semi-circular portion 14^b which extends around the upper portion of the cylindrical section of 85 the water tank and connects this section to the plate 12, making a very rigid construction.

At the front end of the tender are the 90 rectangular boxes 15 of the usual type.

17 is a transverse reinforcing plate secured to the portions 5^b of the dash plates and secured at its upper end to the inclined plate 11 as clearly shown in Fig. 1. 18 are transverse angle-bars curved to fit the lower section of the water tank, and two of these bars extend above the side seams and are secured to the upper plates of the water tank. 95

When the space α under the bottom plate 9 is used for housing a mechanical stoker, then an opening is provided in the inclined plate 11 and a door 11^a closes this opening. An opening 11^b is also formed in the plate 9 under the door as shown in Fig. 8 to 105 allow access to the space α .

When the space α is used as a part of the water chamber, then the plate 10 is cut away as shown to connect the space α with the main water space of the tender, see 110 Fig. 1.

It will be understood that all available

space not used for fuel and tools is used for water.

I claim:

1. The combination in a tender tank of a locomotive, of a semi-cylindrical bottom section extending the full length of the tender; an upper section of the water tank secured to the lower section and having a single longitudinal seam at the top; an end plate; and a fuel box located on the semi-cylindrical section in front of the cylindrical portion of the water tank and having inclined sides.

2. The combination in a tender tank, of a water section having a semi-cylindrical bottom plate; a semi-cylindrical top section forming with the bottom section a complete cylinder, said top section forming substantially, one half of the tank of the tender; a rectangular section having a fuel box, mounted on the front portion of the semi-cylindrical bottom plate; an angle-bar having a longitudinal section at each side and having a curved section extending over the water section and securing the upper plates of the water section to a transverse plate which forms the end plate of the water section.

3. The combination in a cylindrical tender tank, of a cylindrical section; a semi-cylindrical section having a flat upper surface forming the floor of a fuel box; side walls extending from the said flat upper surface; inclined plates at each side of the fuel box and extending to the side walls; and an inclined plate at the rear of the fuel box extending to the end plate of the cylindrical section.

4. The combination in a cylindrical tender tank, of a cylindrical section; a semi-cylindrical section having a flat upper surface forming the floor of a fuel box; side walls extending from the said flat upper surface; inclined plates at each side of the fuel box and extending to the side walls; an inclined plate at the rear of the fuel box extending to the end plate of the cylindrical section; and two horizontal portions coupling the bottom plate at each side of the fuel box to the semi-cylindrical section.

5. The combination in a tender tank, of a cylindrical section; a semi-cylindrical section forming a continuation of the cylindrical section; a rectangular fuel box mounted above the semi-cylindrical section; and longitudinal dash-plates reinforcing the structure and connecting the lower portion of the semi-cylindrical section with the bottom of the fuel box.

6. The combination in a tender tank, of a cylindrical section; a semi-cylindrical section forming a continuation of the cylindrical section; a rectangular fuel box section mounted above the semi-cylindrical section; longitudinal dash-plates reinforcing the structure and connecting the lower portion of the semi-cylindrical section with the bottom of the fuel box, said dash-plates extending above the bottom plate and forming the lower side walls of the fuel box; and inclined plates at each side of the fuel box connecting the upper edges of the dash-plates with the side walls.

ELMER E. HICKEN.
